UNITED STATES PATENT OFFICE.

MARK D. STILES, OF MOUNT VERNON, NEW YORK.

DESIGN FOR A MAT-BINDER.

SPECIFICATION forming part of Design No. 31,165, dated July 4, 1899.

Application filed June 7, 1899. Serial No. 719,722. Term of patent 3½ years.

To all whom it may concern:

Be it known that I, MARK D. STILES, a citizen of the United States, residing at Mount Vernon, in the county of Westchester and State of New York, have invented and produced a new and original Design for a Mat-Binder; and I do hereby declare the following to be a full, clear, and exact description of the same, reference being had to the accompanying drawings, forming a part thereof.

The drawings represent, in Figure 1, a perspective view of the mat-binder or border, and in Fig. 2 a cross-section thereof.

The design relates to the configuration of the binder.

The leading features of the design appear in the following description.

The binder is formed of thin metal having a cross-section, as seen in Fig. 2, of a substan-

tially L shape, with the two sides of substantially the same width.

Upon the sides and ends of the binder A are the lugs or flanges B, which project from the same at right angles to the front face and in the general direction with the side of the binder which lies at right angles to the said front face. These lugs or flanges project to a considerable distance beyond the rear edge of the said side, as shown.

What is claimed as new is—

The design for a mat-binder substantially as shown and described.

In testimony whereof I affix my signature in presence of two witnesses.

MARK D. STILES.
